PROPELLER

Le Roy Martens, 1633 Palmyra Ave., Orange, Calif.

Filed Mar. 15, 1965, Ser. No. 84,272

Term of patent 14 years

(Cl. D71—1)

FIG. 1 is a side elevational view of a propeller embodying my design;

FIG. 2 is a side elevational view of the same rotated 60° from the position of viewing in FIG. 1;

FIG. 3 is a rear end elevational view of the same; and

FIG. 4 is a front end elevational view of the same.

I claim:

The original design for propeller, as shown.
